202,041

DENTAL SYRINGE

Karl H. Burzlaff, Fairport, N.Y., assignor to Ritter Company, Inc., Rochester, N.Y., a corporation of Delaware

Filed Oct. 5, 1964, Ser. No. 82,034

Term of patent 14 years

(Cl. D24—1)

FIG. 4

FIG. 5

FIG. 1 is a side elevation of a dental syringe showing my new design; the broken lines are shown for illustrative purposes only;

FIG. 2 is a top view of FIG. 1;

FIG. 3 is a bottom view of FIG. 1;

FIG. 4 is a front elevation thereof; and

FIG. 5 is a rear elevation thereof.

I claim:

The ornamental design for a dental syringe substantially as shown and described.
